TEAKETTLE

Richard B. Cronheim, 411 N. 7th St., St. Louis, Mo.

Filed Aug. 23, 1961, Ser. No. 66,472

Term of patent 14 years

(Cl. D44—25)

FIG. 1

FIG. 2

FIG. 3

FIG. 4

FIG. 1 is a side elevational view of a teakettle embodying my new design, as viewed from one side;

FIG. 2 is a side elevational view thereof, as viewed from the opposite side;

FIG. 3 is a top plan view thereof; and

FIG. 4 is a bottom plan view thereof.

I claim:

The ornamental design for a teakettle, substantially as shown.
